ATTORNEY

UNITED STATES PATENT OFFICE.

WILSON W. WEIR, OF BROOKLYN, NEW YORK.

ROTATABLE TOOTHBRUSH.

Application filed February 16, 1925. Serial No. 9,474.

This invention relates to tooth brushes of the rotatable type.

A general object of the invention is to provide a device of the general type referred to in which the rotatable brush member is supported adjacent both ends for effective operation without lateral yielding.

The invention includes a brush guard or shield member which protects the mouth from the action of portions of the brush not directly engaged in cleansing the teeth. The guard member is equipped with a bearing support for the brush adjacent the free end thereof and provides a seat in which an end tuft on the brush operates for application to a local and restricted portion of the dental surface.

Another feature of the invention resides in the provision of a simple and effective actuating mechanism for the brush shaft, the mechanism forming part of a handle member and provided with a guard member for preventing engagement of the actuating mechanism with the lips or face of the user.

Other features of the invention will be hereinafter referred to.

In the drawings, in which a preferred embodiment of the invention has been selected for illustration,

Figure 1 is a view in longitudinal section of a tooth brush embodying the invention.

Figure 2 is a side view partly in section of the device shown in Figure 1.

Figure 3 is a view in cross-section taken on the line 3—3 of Figure 1.

Figure 4 is a sectional view taken on the line 4—4 of Figure 1.

Figure 5 is a sectional detail view taken on the line 5—5 of Figure 6.

Figure 6 is a sectional detail view taken on line 6—6 of Figure 5.

Referring to the drawings for a more detailed description of the invention, a tooth cleaning device of the rotatable brush type is shown in which a frame member 10 includes an elongated stem portion 11 having an elongated axial opening 12 therein to provide a housing for a rotatable shaft 13 which is journaled in the stem portion of the framework 10. The frame member provides a bearing support at 14 for the rear portion of the shaft 13 and a bearing support at 15 for a forward portion of the shaft.

The rotatable shaft 13 is provided at its rearward end with a toothed pinion 16 through which the shaft may be rotated and

at its forward end with a chuck member 17 for engaging and rotating the stems of rotatable brushes which may be engaged therein.

At the rear portion of the stem 11 the frame member is expanded into a shield or guard member 18 which has a rounded and smooth outer surface particularly designed to prevent injury to the lips or face of the user of the device. The guard 18 provides also a partial housing or casing for operating mechanism employed to rotate the shaft 13 and the brush member operated thereby. The operating mechanism referred to consists of a pair of levers 19 pivotally mounted at 20 adjacent the ends of rearwardly extending support or bracket members 21 preferably formed integrally with the frame member 10. The levers 19 are normally moved to and held in positions separated from each other to their maximum extent by means of a spring device 22 mounted on the pivot pin 20 and engaging the inner surfaces of the levers 19 as is clearly shown in Figures 1 and 2 of the drawing. The levers 19 at their forward ends are provided with angular extensions 23 which project toward and into overlapping engagement with each other and in flanking engagement with the toothed pinion 16 formed on the rearward end of the rotatable drive shaft 13. The angular extensions 23 of the levers 19 are toothed or serrated on their pinion engaging surfaces so as to operate the pinion in the movement of the members 23 which is produced by the closing of the levers 19 toward each other under pressure of the hand of the user, or of the separation of the levers 19 under the action of the spring 22. In order to prevent disengagement of the toothed members 23 from the pinion 16 the members 23 are provided with longitudinal slots 24 in which pins 25 carried by the members 23 engage. It will be seen that with this arrangement each member 23 is provided at its extremity with a pin 25 which engages and slides in the slot 24 in the other member thereby preventing separation of the parts and guiding the movement of the parts in operation.

The forward end of the frame member 10 is provided with a hollowed-out guard member 26 which has an elongated extension open along one side thereof as is clearly shown in Figure 1 of the drawings. Within the guard member 26 a rotatable brush 27 is adapted to be mounted, the extending end 28 of the stem of the brush being adapted to be fitted into

the chuck member 17 forming the adjacent extremity of the rotatable shaft 13.

In order to facilitate the operation of the brush 27 and provide adequate support therefor in operation, the guard member 26 is provided with a septum or partition wall 29 adjacent the forward extremity thereof. The partition member 29 provides a bearing support for a forward portion of the shaft or stem 10 of the brush 27 as is clearly shown in Figure 2 of the drawing. For this purpose the partition 29 is provided with a shaft receiving recess 30 into which the shaft of the brush may be placed. A clip or holding member 31 pivoted at 32 on the member 29 may be swung into and out of locking relation to the recess 30 to hold the shaft therein or to release it for removal therefrom.

Another feature of the invention resides 20 in the provision of a tufted extremity 33 on the forward end of the brush and of a seat or recess 34 in the forward end of the guard member 26 for receiving the tufted brush member 33 therein. With this construction a 25 protruding tuft 33 of brush bristles is provided for local application to a restricted portion of the dental surfaces.

With the construction described the brush members 27 may be readily interchanged as 30 desired or removed from their position within the guard member 26 to provide access to the parts for cleansing thereof.

In operation a brush member 27 is placed 35 in position within the operating chuck 17 and in the bearing recess 30. The lever members 19 are then ultimately pressed toward each other to cooperate with the spring 22 in the oscillation or reciprocation of the toothed members 23 to produce corresponding alternate rotation of the brush member 27 at a rel-

ative speed. The bearing support of the brush adjacent its opposite ends provides a firm and substantial construction and facilitates the effective use of the device in practice. A further useful application of the 45 brush is provided by the tufted construction at the extreme end portion thereof.

What I claim is:—

1. In a rotatable tooth brush, a cylindrical brush having an end tuft, a guard extending 50 longitudinally of the brush and open along one side thereof, said guard being provided with a bearing support adjacent each end of the brush, one end of the guard forming a seat, and the tufted extremity of said brush 55 operating in said seat outside the adjacent bearing support, said brush guard being open at its outer extremity to permit the protrusion of the tufted extremity of the brush there-through; and said brush being removably 60 mounted for withdrawal laterally from its position in the outer end of said guard and longitudinally from its position in the other end.

2. In a tooth brush of the rotatable type, 65 a frame, a cylindrical brush mounted on a stem and having an end tuft, a brush guard extending from said frame longitudinally of the brush, partially encircling the same and having an open end through which said end 70 tuft protrudes, a bearing seat in the brush guard at a point spaced a short distance from the open end to afford a bearing support for the outer portion of the stem of said brush, and means to engage with the inner end of the 75 stem for rotating the said brush.

Signed at New York, in the county and State of New York, this 23rd day of January, 1925.

WILSON W. WEIR.
